UNITED STATES PATENT OFFICE.

CLARENCE A. VAN DERVEER, OF WAKEFIELD, MASSACHUSETTS, ASSIGNOR TO HEYWOOD BROTHERS AND WAKEFIELD COMPANY, OF WAKEFIELD, MASSACHUSETTS, A CORPORATION OF NEW JERSEY.

UPHOLSTERED STRUCTURE AND FABRIC THEREFOR.

1,213,559.

Specification of Letters Patent. Patented Jan. 23, 1917.

Application filed December 28, 1915. Serial No. 69,007.

To all whom it may concern:

Be it known that I, CLARENCE A. VAN DERVEER, a citizen of the United States, residing at Wakefield, in the county of Middlesex and State of Massachusetts, have invented new and useful Improvements in Upholstered Structures and Fabric Therefor, of which the following is a specification.

This invention relates to upholstered structures in which woven cane fabric is used for the external covering. Woven cane fabric is used extensively for seats and seat backs used in public conveyances such as railroad cars, and in some cases the seat backs are formed to provide a headroll, a neck, and a bustle, such form of back conforming substantially to the neck, shoulders, and back of the occupants. In order to give a seat back such form it is necessary to crease or indent the woven cane fabric on lines corresponding to the junction of the head-roll and neck and to the junction of the neck and bustle, and to hold in the fabric at the said junctions to maintain the desired form and appearance of the back. This has been done hitherto by sticking a stitch-receiving strip of soft woven fabric, such as canvas, to the back of the cane fabric or to the lining, if the cane fabric has a lining, and by sewing the said strip to the inner structure of the back, by stitches drawn tight to crease or indent the cane fabric. In such cases the cane fabric is dependent upon adhesive material for its creased formation and is constantly tending to pull away from the stitch-receiving strip. This is especially objectionable when glue is the adhesive substance, because some railroads wash the cane fabric from time to time, and the water softens the glue, so that the cane fabric is released and springs away from the fastening strip. It is thereafter impossible to restore the original shape of the cane fabric without driving metallic fasteners through it and into the wooden frame upon which the structure is built. The driving of metallic fasteners through the cane fabric as hitherto made splits the woven members, and in time the heads of the fasteners will pass through the cane and the latter will be again released and spring away from the upholstering material, and it will be in a worse condition than formerly

because of the injury caused by the splitting of the cane and by the passing of the metallic fasteners therethrough.

The object of the present invention is to provide a woven cane fabric capable of receiving fasteners without being split, and to provide an improved upholstered structure, such as a seat back, in which my improved cane fabric is used with fasteners to set it in on one or more lines to impart and maintain a creased external surface.

The characteristic feature of the woven cane fabric is that it has one or more woven members made of some material less brittle than cane and such member or members are arranged to register with the creases or grooves which are to be imparted to the finished structure. The less brittle member may be a cord or a wire, and its function is to receive the fasteners which are used to impart the creased or indented formation. Such fasteners may be anchored directly to some element of the inner structure behind the upholstering material. If it is desired to fasten the external cane fabric to the wooden frame, metallic staples may be driven into the latter and arranged to straddle the cord or wire or other member woven into the cane fabric, especially for that purpose. On the other hand, if the internal structure includes a layer of woven fabric capable of having a sewing needle passed through it readily, stitches may be used as the means for fastening the external cane fabric to the inner structure, and in such case each stitch would pass around the cord or wire or other member of the woven cane fabric and would be anchored in the woven fabric of the inner structure.

Of the accompanying drawings: Figure 1 represents conventionally a sheet of woven cane fabric having a wire and a cord woven therein to receive fasteners. Fig. 2 represents an elevation, on a larger scale, of a small piece of such fabric including a portion of the cord. Fig. 3 represents a sectional view through the structure intersected by line 3-3 of Fig. 2. Fig. 4 represents a sectional view in the plane indicated by line 4-4 of Fig. 2. Fig. 5 represents a sectional view of a portion including the wire. Fig. 6 represents a vertical sectional view of an upholstered seat-back formed to provide a

head-roll, a neck, and a bustle. Fig. 7 represents a vertical sectional view, on a larger scale, of the portions adjacent the junction of the head-roll and neck, showing stitches for holding the woven cane fabric. Fig. 8 represents a vertical sectional view of the portions adjacent the junction of the neck and bustle, and showing metallic fasteners instead of stitches to hold the woven cane fabric.

The same reference characters indicate the same parts wherever they occur.

A sheet of woven cane fabric is indicated as a whole at 10. It is composed essentially of warp members 11 of cane and filling members 12 of cane. For a seat back the cane fabric is usually arranged so that the warp members extend transversely and the filling members extend up and down. In the present instance two special fastener-receiving members 11^a and 11^b are interwoven with the cane members 11 and 12, and each of said fastener receiving members is a warp member, and is arranged between two cane members 11. For other uses it might be desirable to arrange the fastener-receiving members, or only one of them, so that they would be filling members instead of warp members, and the invention, in its broadest aspects, contemplates the latter arrangement. The characteristic feature of the special fastener-receiving members is that they are stronger and less brittle than cane. The member 11^a is represented as a cord, and the member 11^b is represented as a wire.

The piece of fabric shown by Fig. 1 is woven and cut for a seat back of the type shown by Fig. 6, and in this instance the seat back calls for two fastener-receiving members. One fastener-receiving member would be sufficient for a seat back of some other type. Aside from the members 11^a and 11^b the cane fabric is similar to the cane fabrics hitherto used for seats and seat backs. It would be within the scope of the present invention to use two wires or two cords instead of one of each, or to interchange the wire and cord. In any event, for a seat back of the type shown, one of the fastener-receiving members would be arranged to register with the junction between the head-roll and neck of the seat back, and the other would be arranged to register with the junction between the neck and bustle of the seat back, as will be understood after further description.

The seat back illustrated by Fig. 6 is formed to provide a head roll indicated as a whole at 15, a neck indicated as a whole at 16, and a bustle indicated as a whole at 17. The back comprises a wooden frame including a transverse top board 18, a transverse bottom board 19, and a transverse intermediate board 20. The ends of these boards are connected by upright boards such as that

indicated at 21. A series of upright slats 22 extend from the bottom board 19 to the intermediate board 20 to brace the bustle portion of the back. The head-roll includes a row of helical compression springs such as 70 that indicated at 23, and they are seated against the board 18. The neck portion 16 is provided with a row of helical compression springs such as that indicated at 25, and the bustle portion is provided with helical compression springs such as those indicated at 26, 26. The springs are confined by woven fabric 27, but thin steel plates 28 are arranged between the ends of the springs and the fabric 27 to protect the latter from the chafing action of the springs. The fabric 27 may be a sheet of burlap, canvas, or duck, extending throughout the width of the seat back, or it may comprise a plurality of relatively narrow strips or webs of sufficient width to sustain the plates 28.

The wooden frame, the springs, the plates 28, and the fabric 27 constitute what is hereinafter termed the "inner structure." These elements are assembled before the upholstering material and the external covering are applied. It will not be necessary to describe the method of procedure followed in assembling the inner structure, excepting to state that the fabric 27 is put under tension vertically and is fastened to the wooden frame in a taut condition to maintain initial deflection of the helical compression springs. The fabric 27 is fastened to the upper edge of the top board 18 by tacks 29 and to the lower portion of the same board by tacks 30. It is fastened to the upper portion of the board 20 by tacks 31, and to the lower portion of said board by tacks 32, and it is fastened to the lower edge of the board 19 by tacks 33.

Although I have described the internal structure and arrangement of the elements as shown, it is not to be understood that the invention is limited to this specific form of structure, nor to this specific arrangement of elements.

After the inner structure has been assembled, the upholstering material is put in place and held temporarily by any suitable means (not shown). For a back of the type to which this invention relates, the upholstering material is divided into sections to enable the external covering of woven cane to be drawn in or indented between the contiguous sections. In accordance with this requirement the upholstering material is shown as being divided into sections indicated at 34, 34, 35, 35, and 36, 36, said sections being arranged to build out the head-roll, neck portion, and bustle portion, respectively.

It will not be necessary for the purposes of the present invention to specify the material of which the upholstering elements 130

are composed, for such material will be selected according to the quality or grade of structure desired.

The piece of woven cane fabric shown by Fig. 1 is sufficient to cover one side of the seat back, and consequently two sheets such as that shown by Fig. 1 will be required to cover such seat back. The outer covering may, though not necessarily, be attached according to the following description. The upper edge 10^a will be fastened to the top edge of the board 18 by driving tacks 37 into the latter. Care will be taken to have the fastener-receiving member 11^a 10 register with the junction of the head-roll and neck portion when the outer covering is drawn down with sufficient stress to compress the upholstering material of the head roll. If it is desired to use stitches, as indicated at 38, to fasten the member 11^a to the inner structure, that portion of the covering 10^a which lies below the member 11^a may be turned outwardly and upwardly to facilitate the passage of the sewing 15 needle, which is usually curved, around the member 11^a from the inner side of the covering. Such stitches will be anchored in the woven fabric 27 of the inner structure and will be drawn in with considerable tension 20 to crease or indent the outer covering. They will not be visible outside the covering, because each stitch will lie behind and be concealed by a cane member 12 as indicated by dotted lines in Fig. 2.

25 After the member 11^a has been fastened by a series of fasteners, the member 11^b will be fastened by another row of fasteners, for example staples, as indicated at 41. When staples are used they will be driven 30 into the board 20 of the wooden frame. After the desired number of fasteners 41 have been driven, the lower edge 10^b of the covering will be fastened to the lower edge of the board 19 by tacks 40, but such fastening may be deferred till the other covering 10 has been applied to the opposite side 35 of the back, and the two lower edges may be fastened simultaneously by the same tacks 40.

40 Although I have shown and described stitches for fastening the member 11^a, and metallic staples for fastening the member 11^b, it would be within the scope of this invention to use staples for fastening the member 11^a and stitches for fastening the member 11^b. Furthermore, stitches might be used for fastening both, or staples might be used for fastening both, the substance of which the members 11^a and 11^b are composed having nothing to do with the character of the fasteners used. When staples are used, their outer ends would be visible upon the external surface of the cane fabric, but when stitches are used they would be 50 concealed by the members 12 as indicated

by dotted lines in Fig. 2, and for this reason stitches would be the preferable means if it were desired to have the fasteners wholly concealed.

I claim:

1. A woven fabric consisting essentially of warp members of cane and filling members of cane but having one or more stronger members of less brittle material of substantially circular cross section woven there- 70 in between the cane members. 75

2. A woven fabric consisting essentially of warp members of cane and filling members of cane but having one or more stronger warp members of less brittle material of substantially circular cross section woven 80 therein between the cane warp members.

3. A woven fabric consisting essentially of warp members of cane and filling members of cane but having a cord woven there- 85 in between two cane members.

4. An upholstered structure comprising a fastener-receiving element, an external covering fabric of cane warp members, cane filling members, and a member less brittle 90 than cane, said cane members and said less brittle member being interwoven with each other, said fabric having a crease, and said less brittle member being arranged to lie in said crease, two substantially contiguous 95 sections of upholstering material between said fastener-receiving element and said external covering fabric, and a series of fasteners each anchored to said fastener-receiving element and embracing said less brittle 100 member, said fasteners extending between said sections of upholstering material.

5. An upholstered structure comprising a fastener-receiving element, an external covering of woven cane fabric having an 105 interwoven member less brittle than cane, two substantially contiguous sections of upholstering material between said fastener-receiving element and said external covering, and a series of fasteners each anchored 110 to said fastener-receiving element and embracing said woven member, said fasteners extending between said sections of upholstering material.

6. An upholstered structure comprising 115 an inner structure including a layer of woven fabric, an external covering of woven cane fabric having an interwoven member less brittle than cane, two substantially contiguous sections of upholstering material between 120 said inner structure and said external covering, and a series of stitches each anchored to said fabric of said inner structure and embracing said woven member of said external covering, said stitches extending 125 between said sections of upholstering material.

7. An upholstered seat-back comprising a 130 fastener-receiving element, an external covering of woven cane fabric having an inter-

woven member less brittle than cane, two substantially contiguous sections of upholstering material between said fastener-receiving element and said outer covering, one of said sections being arranged to form a head-roll and the other being arranged to form the neck of the seat-back, and a series of fasteners each anchored to said fastener-receiving element and embracing said woven member of said outer covering, said fasteners extending between said sections of upholstering material.

8. An upholstered seat back comprising a fastener-receiving element, an external covering of woven cane fabric having an

interwoven member less brittle than cane, a section of upholstering material arranged to form the bustle of said seat-back, a section of upholstering material arranged to form the neck of said seat-back, said woven member being arranged to register with the junction of said bustle and neck, and a series of fasteners each anchored to said fastener-receiving element and embracing said woven member, said fasteners extending between said sections of upholstering material.

In testimony whereof I have affixed my signature.

CLARENCE A. VAN DERVEER.
